ABSTRACT: A corona assembly for use with electrostatic copy machines, including a fixed bracket element of generally trapezoidal shape, a shield element having a first portion of corresponding configuration slideably engageable therewith, a corona wire of generally rectilinear configuration, a pair of planer diverging walls surrounding said corona wire, a pair of end blocks supported by said diverging walls at the end portions thereof, and supporting said wire at each of two terminals thereof, said diverging walls allowing ionized air disposed therebetween to readily escape to reduce the possibility of arcing.

PATENTED SEP 28 1971

CORONA ASSEMBLY FOR ELECTROSTATIC COPY MACHINES

This invention relates generally to the field of xerographic-type copying machines, and more particularly to an improved corona assembly suitable for use in such devices.

In the prior art, it is known to use a pair of such devices, which operate at very high voltages, in the order of 6,000 volts at 60 cycle frequency. An electrostatic field is induced surrounding the wire, which is used to charge the paper, portions of this charge being subsequently altered by exposure to a light image, whereby toner particles will adhere to those areas of the paper which are not affected by light.

It is common practice to use an upper and a lower corona wire, which is normally required where the copying device is operated in a high humidity atmosphere. Unfortunately, this construction requires a duplication of parts, and in prior art constructions, there has been a common tendency for the wire to arc with respect to surrounding structure, and thus burn itself out.

It is among the principal objects of the present invention to provide an improved corona assembly, in which all of the paper charging function can be performed at a single station, using much higher voltages than those which have been previously used, and with a complete absence of arcing.

Another object of the invention lies in the provision of an improved corona wire assembly of the class described, which may be readily removed for servicing, and as readily reinstalled.

A further object of the invention lies in the provision of an improved corona wire assembly construction, in which the number of component parts has been materially simplified, thereby reducing the process of manufacture and assembly.

Yet another object of the invention lies in the provision of an improved corona wire shield which is shaped to permit maximum charging of paper passing therebeneath, and which includes means for venting ionized air to the outside atmosphere, thereby reducing the likelihood of arcing occurring, with subsequent burn-out of the corona wire.

These objects, as well as other incidental ends and advantages, will more clearly appear in the progress of the following disclosure, and be pointed out in the appended claims.

In the drawing, to which reference will be made in the specification, similar reference characters have been employed to designate corresponding parts throughout the several views.

FIG. 1 is a fragmentary exploded view in perspective of an embodiment of the invention.

FIG. 2 is a fragmentary view in perspective of the embodiment showing the parts in fully assembled condition.

FIG. 3 is a fragmentary view in perspective as might be seen from the left-hand portion of FIG. 2.

In accordance with the invention, the device, generally indicated by reference character 10, comprises broadly: a mounting element 11, a shield element 12, and corona wire support means 13.

The mounting element 11 includes first and second bracket means 17 and 18, respectively, each having a mounting flange 19 with a mounting slot 20 whereby the same may be attached to the frame of the copying device (not shown). The mounting flange 19 is connected through a bend portion 21 to a second

flange 22, and by a bend portion 23 thereon to a horizontally disposed flange 24. A spot-welded area 25 on each horizontal flange 24 interconnects with a trapezoidally shaped member 26 including a base wall 27 and angularly disposed walls 28 and 29 which define therebetween a "dovetail" into which the shield element 12 may be positioned.

The shield element 12 is preferably formed of sheet metal similar to that of the mounting element 11, and includes a correspondingly trapezoidally shaped portion 34 having a base wall 35 and a pair of converging walls 36 and 37. Interconnected with the walls 36 and 37 are diverging walls 38 and 39. An end wall 40 is formed integrally with the base wall 35, and includes a pair of tabs 42 which are spot-welded to one end of each of the walls 38 and 39. It will be noted that the vertical portion 43 thereof defines a pair of openings 44 which, as will more fully appear, permit the escape of ionized air surrounding the corona wire support means 13. A central opening 45 permits the entry of screw means 46 which serve to position a part of the support means 13.

20 The support means 13 includes a pair of mounting blocks 50 and 51, preferably of die-cast construction, and defining converging sidewalls 52, an end wall 53, an upper wall 54, and a lower wall 55. A rectangular cavity 56 opens to a threaded bore 57 in an inwardly disposed wall 58, whereby a wire-retaining member 59 may be positioned by means of a screw 60. The corona wire itself is a magnet tungsten wire loop of approximately 0.003 diameter, reference character 60.

25 Power is provided through conductors 63, which are connected to a filtered 12,000 volt source of well-known type. It will be observed that the angle of the diverging walls 38 and 39 allows pocketed ionized air to escape, through the one inch interstice between the free edges thereof and the sensitized paper being charged (not shown). Because of the divergence of the walls, there is a smaller volume of air disposed within the shield, thereby permitting a quicker charge of the paper as it passes therebeneath.

30 I wish it to be understood that I do not consider the invention limited to the precise details of structure shown and set forth in this specification, for obvious modifications will occur to those skilled in the art to which the invention pertains.

35 I claim:

1. A corona assembly for use with an electrostatic copying device comprising: a mounting element, a shield element, and a corona wire support means; said mounting element having attachment means thereon for securing the same in fixed relation with respect to said copying device, and means forming a slideably engageable socket; said shield element including a portion of configuration corresponding to that of said socket, a base wall lying in the first plane, a pair of sidewalls interconnected to said base wall, and mutually diverging in a direction away from said plane, said corona wire support means including first and second mounting blocks of tapered configuration and secured in contact with said sidewalls at opposite ends thereof; said blocks forming openings leading to the area enclosed by said sidewalls to permit the passage of air therethrough; and corona wire-engaging means on said blocks for supporting the same in rectilinear condition there between; said corona wire being supported substantially parallel to and adjacent the free edges of said pair of sidewalls.
